APPARATUS FOR FILLING SIPHON-BOTTLES.

1,073,366.

Specification of Letters Patent.

Patented Sept. 16, 1913.

Application filed August 20, 1910. Serial No. 578,210.

To all whom it may concern:

Be it known that I, JOHN A. SCHULTZ, Jr., a citizen of the United States, residing at Newark, in the county of Essex and State of 5 New Jersey, have invented certain new and useful Improvements in Apparatus for Filling Siphon-Bottles, of which the following is a specification, reference being had thereto in the accompanying drawings, which 10 form a part thereof.

My invention relates to apparatus for filling siphon bottles, and more particularly to a type thereof adapted to charge the bottle with carbonic acid gas prior to the delivery of the charged fluid thereinto.

The main object of my invention is to provide an apparatus of this character wherein the carbonic acid gas, substantially unmixed with air, may be charged into an empty 20 siphon bottle prior to the delivery of charged water thereinto, and the apparatus continued in use for an extended period, using the carbonic acid gas repeatedly without material deterioration in the quality of 25 such gas.

A further object is to provide an apparatus of this character, wherein the siphon may be "snifted" or vented into the tank containing the carbonic acid gas, and said 30 gas tank will be automatically vented to maintain a substantially constant, uniform pressure therein.

A still further object is to provide an apparatus of this character wherein carbonic 35 acid gas only will be delivered to the siphon bottle from the gas tank, and any water discharged into said tank when the bottle is "snifted" or vented will be automatically discharged from the tank, thus preventing 40 the delivery of "flat" water to the siphon with the initial charge of gas, and insuring uniformity in the quality of the bottled water.

A still further object is to provide an apparatus of this character wherein any air 45 discharged into the carbonic acid gas tank, may be discharged from said tank from time to time, to prevent the accumulation of air in this tank and a resultant initial charging 50 of the bottle therewith, alone or in substantial volume mixed with the gas. And a still further object is to provide an apparatus of this character, of simple design and so constructed and arranged as to take advantage of the stratification of water, car- 55

bonic acid gas, and air in the gas tank, to insure the delivery of substantially pure carbonic acid gas to the siphon bottle.

The invention consists in the novel features of construction and combination of 60 parts hereinafter set forth and described and more particularly pointed out in the claims hereto appended.

In the accompanying drawing I have shown a front elevation of an apparatus embodying my invention, the carbonic acid gas tank being shown in vertical section to disclose the interior arrangement thereof.

In the art of filling siphon bottles, water previously charged with carbonic acid gas under pressure ranging from one hundred to two hundred pounds is, in some instances, delivered from a tank to the bottle, prior to the filling of the bottle, a vent or "snift" valve being arranged in the pipe line between the filling nozzle and the water tank to destroy the equilibrium of pressure in the bottle and in the tank when the bottle is partially filled, and to permit the completion of the filling of the bottle with the desired gas pressure upon the top thereof.

There is a constant tendency of the gas to escape from the water when the surrounding pressure is sufficiently low to permit it to escape, and as the charged water is delivered to the bottle filled with air, there is a sufficient loss of the gas to lower the quality of the bottled goods.

Furthermore, as the water is sprayed through the siphon tube into the bottle, there is a still greater tendency of the gas to escape than under normal conditions. To obviate this difficulty, the atmospheric air in the bottle may be displaced by air mingled with pure carbonic acid gas under low pressure, or by gas alone, and thus not only minimize the tendency of the gas in the water to escape therefrom, but provide a volume of carbonic acid gas through which the incoming water is discharged in a spray and thus cause said water, if it has not already absorbed gas to its full capacity, to take up additional gas and thus raise its quality.

The herein described apparatus is so designed as to deliver gas to the siphon bottle in such condition as to insure high efficiency 105 in the above described process, and to permit the filling of a large number of bottles without substantial variance in the condition of the water therein.

In the embodiment of my invention shown 110

in the drawing, which is merely one application thereof, however, adapted to be used in connection with two bottling machines, I have shown at *a*, a bottling machine of any well known, or approved type provided with 5 a combined filling valve *b* and "snift" valve *b'* connected respectively through the pipe *c* with the water tank or carbonator, not shown, and by the pipe *d*, with a low pressure carbonic acid gas tank *e* which may be supported upon a separate standard, as 10 shown, or by the standard of the bottling machine, as desired, the manner of mounting said tank relative to the machine being immaterial to the invention.

15 The tank *e* interiorly thereof is free from obstruction so as to permit the automatic separation and stratification of the air, carbonic acid gas, and water, delivered to the tank while in use, the specific gravity of 20 the three varying in the order named, water being the heaviest.

To insure the delivery of carbonic acid gas with as little air as possible therein, I 25 draw the supply of gas passing through the pipe *d* from a point slightly above the bottom of the tank *e*, through the tube *f*, the upper end of which projects through the top of the tank and is provided with a fitting *g* adapted to coöperate with the pipe *d*. The lower, open end of the tube *f*, it will be observed, is thus disposed within that portion of the tank wherein the carbonic acid gas will stratify, any mixture of air 30 and gas, being of lower specific gravity than the unmixed gas, rising above this point, and thus affording sufficient time for the gas and air to separate and the latter to rise to the top of the tank, a construction made desirable by reason of the fact that with 35 the filling of the bottle, air, or a mixture of carbonic acid gas and air, with or without water, is delivered to the tank *e* through the tube *f*, the pipe *d* being connected with the "snift" valve of the siphon filling machine. 40 The open end of the tube *f* will also be positioned above the bottom of the tank *e* sufficiently to prevent the water accumulated 45 in the bottom of said tank being forced through the "snift" valve into the bottle being filled.

50 Mounted in the top of the tank *e* is a three-way fitting *h* the leads of which are respectively connected with a pressure gage *i*, a vent or pet cock *j* and a union member *k* adapted to be connected with a carbonic acid gas tank for the purpose of filling the tank *e* with carbonic acid gas or replenishing the supply of such gas therein. The fitting *h* 55 opens into the tank *e* at the top thereof, so that the upper strata of air may be vented through the pet cock *j*, thus preventing the accumulation of air within the tank *e* in sufficient volume to result in such air being 60 delivered to the siphon bottle through the 65

tube *f*. The fitting *h*, adjacent to the union member *k*, is provided with an ordinary cut off valve *l* for limiting the supply of gas charged into the said tank. I have shown at *m* a second tube similar to the tube *f*, 70 which permits the tank *e* to be coupled to another filling machine at the same time.

As the bottle is "snifted," a certain amount of water is carried over into the tank *e* and this water accumulates in the bottom of the tank, and the carbonic acid gas previously taken up thereby is disassociated or released from the water to an extent to cause this water to become "flat" and unpalatable, 75 this resulting from the difference in the pressure between the water tank and the tank *e*. This water accumulates in the tank *e* fairly rapidly, and with the accumulation of this water, the pressure in the tank is gradually raised beyond that necessary to secure the 80 highest efficiency of the apparatus. This also varies the conditions under which succeeding siphons are filled, so as to result in a variance in the quality of the bottled water. To obviate this condition, I provide 85 a trap pipe *n* having an automatic blow off valve *o* so set as to operate at substantially that pressure desired within the tank *e*, thus causing the raising of the pressure within the tank to automatically operate 90 this valve to relieve such pressure by the blowing off of the water accumulated in this trap and in the bottom of the tank *e*. I provide the blow off valve *o* with a fitting *p* which may either open into atmosphere or 95 be connected with a gasometer, if it be desired to separate the gas and water and save the former. I have found in practice that the venting of the tank *e* from the bottom thereof is the most effective and most economical in use, although the tank may be 100 vented at any other point thereof if desired.

The operation of the herein described apparatus is substantially as follows: Assuming that the gage *i* shows a low, or no, pressure in the tank *e*, the valve *l* is first opened to admit carbonic acid gas to said tank, this valve being closed when the gage shows approximately forty pounds pressure in said tank, that being substantially the pressure 115 at which the apparatus has the highest efficiency. The tank *e* thus being filled with gas, the bottle is set in the bottling machine in the usual manner and the siphon valve opened, the bottle being inverted so as to 120 permit the filling and "snifting" of the bottle through the tube *f* thereof. The "snift" valve *b'* is then opened to permit the carbonic acid gas, under the low pressure maintained in the tank *e*, to flow into 125 the bottle and displace the atmospheric air contained therein although this may be either mixed with the inflowing gas, or flow back into the tank *e*. When the pressure in the tank *e* and the bottle are equal, the "snift" 130

valve is closed and the filling valve opened to admit water charged with gas under a relatively higher pressure than that of the tank *e*, to flow into the bottle. The inflowing water is thus delivered to the bottle against a pressure of carbonic acid gas of approximately forty pounds, this having the twofold result of preventing the escape of the gas previously absorbed, or taken up, by the water, and causing any water insufficiently charged to take up gas as it is sprayed through the gas contained in the bottle. As the pressure in the bottle is raised until it equals that upon the water in the tank, the equilibrium of pressure prevents the further flow of water to the bottle, thus making it necessary to relieve the pressure in the bottle to insure the filling thereof. To destroy this equilibrium of pressure the "snift" valve *b*' is again opened and the mixture of gas upon the top of the water is vented through the pipe *d*, being discharged into the tank *e*. The pressure in the bottle having thus been lowered, the filling valve *b* is again opened and the valves *b* and *b*' are alternately opened and closed until the desired quantity of water under the desired pressure is in the bottle. As the "snift" valve *b*' is opened, a mixture of air and gas with a small quantity of water carried in suspension therewith, is delivered to the tank *e*, passing downwardly through the tube *f*. The water by reason of its greater specific gravity immediately drops to the bottom of the tank *e*, and the mixed gases having lower specific gravity than the carbonic acid gas in the tank *e*, rise above the open end of the tube *f* where the air and gas become disassociated, the air rising to the top of the tank and the gas entering the gas stratum adjacent to the open end of said tube *f*. My experiments indicate that this separation or disassociation of the carbonic acid gas and air is not instantaneous, requiring but a small interval of time, however; but by drawing the carbonic acid gas delivered to the bottles from a point intermediate the top and the bottom of the tank *e*, I secure a substantially pure carbonic acid gas, unmixed with air; and provide a zone within the tank *e* within which this separation may occur without impairing the efficiency of the machine. Inasmuch as the pressure within the bottle, when it is "snifted", is greater than that within the tank *e*, the gases and air discharged into the tank *e* will gradually raise the pressure in this tank. Before, however, there has been a sufficient increase of the pressure to vary the conditions under which the apparatus operates, the valve *o* will be opened and the pressure within the tank relieved, restoring the pressure in said tank to normal. As heretofore stated, this blowing off operation is accompanied by a discharge of any water

accumulated in the tank *e*, and it is not accompanied by a substantial loss of gas even though a gasometer is not used. After the machine has been in use for some time, say for half a day, the pet cock *j* should be opened and the pressure within the tank *e* reduced by the blowing off of the air accumulated in the top of said tank, the pressure within the tank being subsequently raised by the admission of fresh gas thereto, upon the opening of the valve *l*. 75

In the foregoing description I have used the term "pure carbonic acid gas" to indicate merely a high quality of commercial gas, and have used the word "gas" to indicate carbonic acid gas as distinguished from the air. 80

It is not my intention to limit the invention to the precise details of construction shown in the accompanying drawings, such being merely a showing of one application of the invention which is capable of being varied without departing from the spirit or scope of the invention. 85

Having described my invention, what I claim as new and desire to have protected by Letters Patent is:— 90

1. In an apparatus for filling siphon bottles, the combination with a supplemental tank, normally charged with carbonic acid gas under low pressure, and means whereby said tank may be directly connected with a source of carbonic acid gas under pressure, of a bottle filling machine and a valve mechanism therefor having leads adapted to communicate respectively with a bottle, with a tank containing carbonated water under pressure relatively higher than the normal pressure in said supplemental tank, and with said supplemental tank intermediate the top and bottom thereof, whereby substantially pure carbonic acid gas is delivered from said tank, said valve mechanism being so set that said bottle is alternately placed in communication with said supplemental tank and with a carbonated water tank, whereby the carbonic acid gas from said tank is alternately discharged from said tank into said bottle and from said bottle back into said tank. 100 110 115

2. In an apparatus for filling siphon bottles, the combination with a supplemental tank, normally charged with carbonic acid gas under low pressure, said tank having a pendant tube therein opening inwardly at a point intermediate the top and bottom thereof, and means whereby said tank may be directly connected with a source of carbonic acid gas under pressure, of a bottle filling machine and a valve mechanism therefor having leads adapted to communicate respectively with a bottle, with a tank containing carbonated water under pressure relatively higher than the normal pressure in said supplemental tank, and with said supplemental tank. 120 125 130

mental tank through the top of said pendant tube, whereby substantially pure carbonic acid gas is delivered from said tank, said valve mechanism being so set that said bottle is alternately placed in communication with said supplemental tank and with a carbonated water tank, whereby the carbonic acid gas from said tank is alternately discharged from said tank into said bottle, and from said bottle back into said tank.

3. In an apparatus for filling siphon bottles, the combination with a supplemental tank, normally charged with carbonic acid gas under low pressure, means whereby said tank may be directly connected with a source of carbonic acid gas under pressure, and automatically acting means whereby the pressure in said tank is maintained uniform, of a bottle filling machine and a valve mechanism therefor having leads adapted to communicate respectively with a bottle, with a tank containing carbonated water under pressure relatively higher than the normal pressure in said supplemental tank, and with said supplemental tank intermediate the top and bottom thereof, whereby substantially pure carbonic acid gas is delivered from said tank, said valve mechanism being so set that said bottle is alternately placed in communication with said supplemental tank and with a carbonated water tank, whereby the carbonic acid gas from said tank is alternately discharged from said tank into said bottle, and from said bottle back into said tank.

4. In an apparatus for filling siphon bottles, the combination with a supplemental tank, normally charged with carbonic acid gas under low pressure, means whereby said tank may be directly connected with a source of carbonic acid gas under pressure, and means whereby the upper stratum of air may be drawn off to prevent the lowering of the level of the carbonic acid gas, of a bottle filling machine and a valve mechanism therefor having leads adapted to communicate respectively with a bottle, with a tank containing carbonated water under pressure relatively higher than the normal pressure in said supplemental tank, and with said supplemental tank intermediate the top and bottom thereof, whereby substantially pure carbonic acid gas is delivered from said tank, said valve mechanism being so set that said bottle is alternately placed in communication with said supplemental tank and with a carbonated water tank, whereby the carbonic acid gas from said tank is alternately discharged from said tank into said bottle, and from said bottle back into said tank.

5. In an apparatus for filling siphon bottles, the combination with a supplemental tank, normally charged with carbonic acid gas under low pressure, means whereby said

tank may be directly connected with a source of carbonic acid gas under pressure, automatically acting means whereby the pressure in said tank is maintained substantially uniform, and means whereby the upper stratum of air may be drawn off to prevent the lowering of the level of carbonic acid gas, of a bottle filling machine and a valve mechanism therefor having leads adapted to communicate respectively with a bottle, with a tank containing carbonated water under pressure relatively higher than the normal pressure in said supplemental tank, and with said supplemental tank intermediate the top and bottom thereof, whereby substantially pure carbonic acid gas is delivered from said tank, said valve mechanism being so set that said bottle is alternately placed in communication with said supplemental tank and with a carbonated water tank, whereby the carbonic acid gas from said tank is alternately discharged from said tank into said bottle, and from said bottle back into said tank.

6. In an apparatus for filling siphon bottles, the combination with a supplemental tank, normally charged with carbonic acid gas under low pressure, means whereby said tank may be directly connected with a source of carbonic acid gas under pressure, a pipe in communication with the bottom of said tank, and a pop valve controlling the outlet of said pipe, whereby pressure within said tank will be automatically maintained substantially uniform, and water accumulated in said tank will be automatically discharged therefrom, of a bottle filling machine and a valve mechanism therefor having leads adapted to communicate respectively with a bottle, with a tank containing carbonated water under pressure relatively higher than the normal pressure in said supplemental tank, and with said supplemental tank intermediate the top and bottom thereof, whereby substantially pure carbonic acid gas is delivered from said tank, said valve mechanism being so set that said bottle is alternately placed in communication with said supplemental tank and with a carbonated water tank, whereby the carbonic acid gas from said tank is alternately discharged from said tank into said bottle, and from said bottle back into said tank.

7. In an apparatus for filling siphon bottles, the combination with a supplemental tank, normally charged with carbonic acid gas under low pressure, means whereby said tank may be directly connected with a source of carbonic acid gas under pressure, means whereby the upper stratum of air may be drawn off to prevent the lowering of the level of the carbonic acid gas, a pipe in communication with the bottom of said tank, and a pop valve controlling the outlet of said pipe, whereby pressure within said tank

will be automatically maintained substantially uniform, and water accumulated in said tank will be automatically discharged therefrom, of a bottle filling machine and a 5 valve mechanism therefor having leads adapted to communicate respectively with a bottle, with a tank containing carbonated water under pressure relatively higher than the normal pressure in said supplemental 10 tank, and with said supplemental tank intermediate the top and bottom thereof, whereby substantially pure carbonic acid gas is delivered from said tank, said valve mechanism being so set that said bottle

is alternately placed in communication with 15 said supplemental tank and with a carbonated water tank, whereby the carbonic acid gas from said tank is alternately discharged from said tank into said bottle, and from said bottle back into said tank. 20

In witness whereof, I have hereunto affixed my signature in the presence of two witnesses this 15th day of August, 1910.
